Laurence Hugo Frederick Warth, Rugby, England, assignor to The English Electric Company Limited, London, England, a British company

Filed Feb. 12, 1957, Ser. No. 639,780

Claims priority, application Great Britain Jan. 31, 1955

1 Claim. (Cl. 60—64)

The present patent application is a continuation in part of the patent application Ser. No. 558,960, now abandoned, of Laurence Hugo Frederick Warth, assignor to The English Electric Company Limited, filed on January 13, 1956.

The invention relates to condensing steam turbines the shafts of which have to be sealed where they pass through the housing against the flow of air into or the flow of steam out of the housing.

This sealing is usually effected by means of steam packed glands having pockets to which steam from an external source is applied as a sealing medium when the internal pressure of the turbine is below atmospheric pressure. In condensing turbines the sealing of these glands usually requires continual adjustment of valves in operation to allow for variations in the internal pressure of the machine, and this is done either by hand or automatically by means of special valves.

According to the present invention, I provide sealing means for the shaft of a steam turbine having at least one turbine housing, a rotor shaft journaled therein, and a main turbine condenser, comprising in combination: a source of sealing steam, glands mounted on the ends of the said turbine housing and extending outwardly therefrom sealing the said rotor shaft with respect to the said housing, pockets being arranged in the said glands at different distances from the interior of the said housing, those pockets which are arranged nearer to the said housing being in direct fluid communication with the said main turbine condenser, and those pockets which are arranged further away from the said housing being in fluid communication with the said source of sealing steam, venting means in fluid communication with the said glands, and additional pockets provided in the said glands, outwardly of the said pockets in fluid communication with the said source of sealing steam, the said venting means being in fluid communication with the said additional pockets. Preferably, it comprises a source of sealing steam, glands mounted on the ends of the said housing sealing the said rotor shaft with respect to the said housing, and venting means, pockets being arranged in the said glands, at least one of the said pockets being in fluid communication on the opposite side of the said source of sealing steam and with the said venting means.

A needle valve is provided between a main isolating valve and a regulating throttle valve in the pipes connecting the source of sealing steam to the associated pockets in the glands at both ends of the turbine.

A pressure gauge is connected to the said pipe downstream of the said needle valve, and this enables the operator to adjust the said needle valve with ease and accuracy when starting up the turbine.

The regulating valves in the pipes leading from the source of sealing steam to the associated gland pockets are initially set in conjunction with the said needle valve (without water yet flowing through the condensers) to give the correct flow of steam to each gland, and to maintain a pressure of, say, 20 p.s.i.g. at the gauge. The regulating valves are then locked in position. Subsequently, when starting up, the operator has only to adjust the needle valve to maintain the reading of the said pressure gauge at the pressure adjusted previously.

This arrangement has proved particularly advantageous

2

for multi-housing turbines where one needle valve only has to be adjusted instead of four or six valves as in the previous arrangements.

In order that the invention may be clearly understood and readily carried into effect, two embodiments thereof will now be described by way of example with reference to the accompanying drawings, in which:

FIG. 1 diagrammatically shows a simple arrangement for a single housing turbine,

FIG. 2 shows a detail of FIG. 1 on a larger scale,

FIG. 3 diagrammatically shows an arrangement for a multi-housing turbine.

Referring first to FIG. 1, the single-housing turbine 1 has a shaft 2 passing through a gland 3 at the high pressure end, and through a gland 3' at the low pressure end of the turbine housing.

The gland 3 at the high pressure end has three consecutive pockets; the pocket 11 in the middle of the gland is connected by a pipe 12 to the main condenser 13 of the steam turbine which has conventional means for producing sub-atmospheric pressure in the condenser 13 indicated diagrammatically as a spray of cold water and a pump for the condensate.

The pocket 14 nearer to the cylinder 1 is connected by a pipe 15 to an intermediate stage of the turbine so as to reduce leakage losses from the high pressure end of the turbine to the condenser.

The pocket 6 farther away from the housing 1 is connected on top to a vent condenser denoted 5 as a whole and to be described in more detail later with reference to FIG. 2, and on the bottom to a pipe 7 which is connected to a source of sealing steam (not shown) with an isolating valve 10, a strainer 16, a needle valve 17 and a regulating valve 8 having locking means 18 arranged in said pipe 7 in succession.

From the said pipe 7 a pressure gauge 19 and a branch pipe 7' branch off between the said needle valve 17 and regulating valve 8. This pipe 7' leads through another regulating valve 8' having locking means 18' to a pocket 26 in the gland 3' at the low pressure end of the housing 1, nearest to this housing. Another pocket 4 farther away from the housing 1 is connected to a vent condenser 5' corresponding to the vent condenser 5 of the gland 3 at the high pressure end of the cylinder 1.

Cooling water is supplied by pipe 21 to a pipe coil 20, and is discharged by pipe 22 (FIG. 2). Steam enters by pipe 25 and is condensed, discharging at the bottom into a tundish 24 and hence to drain. The body is vented at 23 to atmosphere. The said pipe 25 is connected to the top of pocket 6 at the high pressure end of housing 1 or to the pocket 4 at the low pressure end (FIG. 1).

Preparatory to starting up the turbine plant according to FIG. 1, the regulating valves 8 and 8' are initially set in conjunction with the needle valve 17 to give the correct flow of steam to each gland 3, 3', and to maintain a pressure of, say, 20 p.s.i.g. at the gauge 19. This setting is carried out at light load and without water flowing through the vent condensers, so that wisps of steam at the vent can be used as an indication of correct sealing. The regulating valves 8, 8' are then locked in position by the locking means 18, 18', respectively.

Subsequently, when starting up, the operator has to adjust only the single needle valve 17 to maintain the reading of, say, 20 p.s.i.g. on the gauge 19 in order to keep satisfactory sealing conditions at the glands 3, 3'.

The pressure in the pockets 6 of the gland 3 will then be above atmospheric pressure by virtue of the pressure drop of the surplus steam flowing to the vent condenser 5, which itself is at atmospheric pressure.

Referring now to FIG. 3, the high pressure housing 1 and the low pressure cylinder 101 of a multi-housing turbine have their shafts 2 and 102 respectively passing

outside through glands 3, 3', 103, 103', respectively. The gland 3 on the high pressure end of the high pressure housing 1 has four pockets 6, 11, 9 and 14, the last mentioned pocket being nearest to the housing 1. The gland 3', at the exhaust end of the high-pressure housing 1 has two pockets 6', 11', the last mentioned one being nearest to the housing 1.

The low pressure housing 101 is built symmetrically, the two low pressure stages being at the ends, where glands 103 and 103' have pockets 104, 126 and 104', 126' respectively, the pockets 126 and 126' being nearest to the housing 101.

Sealing steam is admitted through a strainer 16, isolating valve 10 and needle valve 17 to a pipe 7 having branch pipes 7', 107 and 107' and a pressure gauge 19 at the first branch point. Each pipe 7, 7', 107, 107' has a throttle valve 8, 8', 108, 108', respectively, each with a locking means 18, 18', 118, 118', respectively, and leads to a gland pocket 6, 6', 126, 126' respectively.

The pockets 11 and 11' are connected by a pipe 12 to a pipe 113 which in normal operation is at a pressure well below atmospheric pressure, for example connected to intermediate stages of the low pressure housing 101 from which low pressure steam is tapped off and passed through pipe 113 to a heater (not shown).

The pockets 6 and 6' of the high pressure housing are connected, at points opposite the connection of these pockets to the sealing steam pipes 7, 7', and to vent condensers 5, 5' of the kind described hereinabove with reference to FIG. 2.

The pockets 104, 104' of the low pressure housing 101 are likewise connected to vent condensers 105, 105' respectively of this type. The pockets 9, 14 at the high pressure end of the high pressure housing 1 are connected to the exhaust end of the said housing 1 and to an intermediate stage of the said high pressure housing 1, respectively, the said intermediate stage being tapped and connected to a heater (not shown) by a pipe 115.

The operation and starting up of the gland system of this plant is similar to that described hereinabove in detail with reference to FIG. 1. It will, however, be noted that a single needle valve 17 serves here for adjusting the supply and pressure of sealing steam to all four glands 3, 3', 103, 103' of both the high pressure

housing 1 and the low pressure housing 101. The advantage of the invention as regards simplicity of operation is accordingly even greater than in the single housing turbine plant according to FIG. 1.

With this arrangement, a reducing valve 27 in line with an isolating valve 30 arranged in a by-pass 29 bridging over the isolating valve 10 and needle valve 17 is used to maintain the pressure of 20 p.s.i.g. except for starting up and shutting down. An impulse connection 10 28 connects the reducing valve 27 with the line 107'. The actual changeover from needle valve 17 to reducing valve 27 or conversely is carried out by opening or closing the isolating valve 30. This arrangement is of particular use when the pressure of the steam supply varies considerably.

What I claim as my invention and desire to secure by Letters Patent is:

Sealing means for the shaft of a steam turbine having a housing having a high pressure end and a low pressure end, a rotor shaft journaled therein, and a main turbine condenser, comprising a combination: a source of sealing steam, a gland mounted on the high pressure end of said turbine housing and extending outwardly therefrom sealing the said rotor shaft with respect to the said housing, annular pockets being arranged in the said gland at different distances from the interior of the said housing, one of said pockets which is arranged furthest from the said housing being in direct fluid communication with said source of sealing steam, an intermediate pocket being in fluid communication with said turbine condenser, and venting means in fluid communication with a pocket which is arranged further from the housing than said intermediate pocket.
